SCOTCH BLOCK

John C. Dockery and Nicholas W. Dockery,
Rockingham, N. C.

Application May 11, 1949, Serial No. 92,680

10 Claims. (Cl. 104—258)

1

This invention relates to an improved wheel stop of the type adapted to be placed on a rail to stop the movement of a railway car when the wheels of the car engage the stop, and is commonly known as a scotch block.

Heretofore, scotch blocks of this type have comprised a vertical plate disposed on top of a rail in the same vertical plane as the rail and having depending centering members secured thereto and extending downwardly therefrom at an angle between the cross ties. This type of scotch block also has a yoke member depending from the vertical block and rigidly secured thereto, and having its lower horizontal portion extending beneath the rail and engaging the lower surface of the rail for securing the block to the rail.

In this old type of scotch block, when the yoke member is secured in proper position the depending members abut against a cross tie and the scotch block is in a relatively stationary position and the full impact of the wheel is absorbed by the cross tie with a severe jolt which very often loosens the scotch block and damages the cross tie.

It is therefore the primary object of this invention to provide a scotch block having clamping means thereon connected by cam means to the yoke member whereby upon impact of the car wheel the cam means will cause the block to be tightened against the rail and further impacts against the block will tend to further tighten the same against the rail to thereby insure a positive stop although the device is used repeatedly.

It is another object of this invention to provide a scotch block having cam activated clamping means thereon to tighten the block against the rail upon impact of a car wheel whereby, upon such impact, force will be exerted substantially downwardly and will be absorbed by the rail and cross tie and the ballast and not by the cross tie alone.

It is another object of this invention to provide a scotch block that may be readily applied to rails of different sizes or gauges and which may be constructed both simply and economically.

It is still another object of this invention to provide a scotch block that may be secured to a rail without drilling the rail or the block of the cross tie as has heretofore been necessary in some instances.

It is a further object of this invention to provide a scotch block having a yoke member oscillatably connected thereto and extending beneath

2

the base of a railroad rail and to provide cam means actuated by the yoke member so that impact of a car wheel will cause the upper portion of the yoke to oscillate slightly in the block to cause the lower portion of the yoke to fit tightly against the base of the rail thus tightening the block against the top surface of the rail.

It is a further object of this invention to provide a scotch block having an arcuate slot which is slidably penetrated by a shaft, opposed ends of which are connected to the upper ends of a U-shaped yoke member. The lower portion of the yoke member extends beneath the base of a rail. Arms are pivotally connected to a cam wheel oscillatably mounted in the scotch block and the cam wheel has an eccentrically located shaft fixed therein to which the upper ends of clamping members are connected, the lower ends of the clamping members being adapted to engage the lower surfaces of the upper flange of the rail.

It is a further object of this invention to provide a scotch block which may be secured to the upper surface of a rail, without the necessity of any means extending beneath the rail, and having clamping means thereon for engaging the lower surfaces of the head portions of the rail to secure the block on the rail, the clamping means being provided with cam means whereby impact of a wheel against the block will tend to tighten the block against the rail.

Some of the objects of the invention having been stated, other objects will appear as the description proceeds, when taken in connection with the accompanying drawings, in which—

Figure 1 is a top plan view of the improved scotch block mounted on a rail;

Figure 2 is a side elevation of the block mounted on a rail and showing a portion of a car wheel abutting against the face of the block;

Figure 3 is a vertical sectional view taken substantially along the line 3—3 in Figure 2;

Figure 4 is a fragmentary side view with parts in section and with parts broken away and showing the cam action associated with the clamping means and is taken substantially along the line 4—4 in Figure 3;

Figure 5 is a sectional plan view taken substantially along the line 5—5 in Figure 2;

Figure 6 is an isometric view of a scotch block showing a modified form of yoke for actuating the cam to which the clamping means is connected;

Figure 7 is a vertical sectional view of the scotch block incorporating the modified form of

yoke and is taken substantially along the line 1—7 in Figure 6;

Figure 8 is an enlarged vertical sectional view through a portion of the modified yoke member associated with the scotch block and is taken substantially along the line 8—8 in Figure 7.

Referring more specifically to the drawings the numeral 10 broadly designates the scotch block proper which comprises a flat plate 11 seated upon and extending upwardly in the plane of a rail 12. This plate 11 is preferably punched or cut from steel plate having a thickness less than the width of the rail head. The front or left-hand portion, in Figures 1 and 2, of the plate 10 is curved substantially in the shape of the periphery of a car wheel, as at 13, and is adapted to be engaged by a car wheel shown at 14 in Figure 2. The plate 11 extends upwardly a distance sufficient to prevent the car wheel 14 from overrunning the plate and is shown of a height substantially equal to the radius of the car wheel. In order to prevent the impact of a car wheel from upsetting the block 10 the plate 11 has a rearwardly extending portion 15 which gives greater length to the plate and provides for a greater base surface resting on the rail 12. An arcuate slot 16 is cut in the plate 11 so that its curvature is the reverse of the plate face 13.

The rail 12 is conventional and may be of any size and comprises a head portion 18, a medial portion 19, and a base portion 20, and is secured by conventional spikes 21 to suitable cross ties 22, only one of which is shown.

Now, in order to secure the block to the rail, a yoke member and cam activated clamping means are mounted on the plate 11 by means of shafts and rocker arms to be presently described. The plate 11 has a bore 24 therein in which a cam wheel 25 is oscillatably mounted, said cam wheel being of substantially the same thickness as the plate 11. Slidably penetrating the cam wheel 25 is a cam shaft 26 which extends through the cam wheel 25 at a point off center its axis and when properly positioned, as in Figure 2, is seen to be positioned to the rear or right-hand side of the cam wheel 25.

Rockers arms 27 and 28 are disposed one on each side of the plate 11 and their right-hand ends in Figure 2 are penetrated by the cam shaft 26 to which they are fixedly secured by welding. The rocker arms 27 and 28 are also fixedly secured to the cam wheel 25 as by welding and may be integral therewith, if desired, so the rocker arms 27 and 28, the cam wheel 25 and the cam shaft 26 will move in fixed relation to each other.

A horizontally disposed shaft 30 extends through the slot 16 in the plate 11 and is adapted for sliding movement therein. The shaft 30 also slidably penetrate the left-hand ends in Figures 1 and 2 of the rocker arms 27 and 28. The shaft 30 extends a distance on each side of the plate outside of the vertically projected plane of the rail 12 and has vertically disposed bores 31 and 32 in opposed ends thereof through which the upper ends of a substantially U-shaped yoke member or bracket 35 slidably extend. The yoke member 35 has vertically disposed arms 36 and 37 to which opposed ends of a horizontally disposed base 38 are welded. The arms 36 and 37 extend through the bores 32 and 31, respectively, of the shaft 30 and are threaded at their upper ends for the reception of suitable nuts 39 and 39'.

It is thus seen that the plate 11 may be secured to the rail 12 by first placing the yoke member

35 in a position so that its base 38 extends underneath the rail 12 and its arms 36 and 37 extend upwardly, and then placing the block on the rail so the arms 36 and 37 penetrate the shaft 30, and then tightening the nuts 39 and 39' against the shaft 30 to thus press the shaft 30 against the bottom of the slot 16 and to hold the plate 11 against the rail 12.

Now, to further assist in securing the plate 11 to the rail 12 and to prevent sliding movement of the scotch block 10 on the rail 12, depending clamping members 40 and 41 are oscillatably and slidably mounted on the cam shaft 26 and depend downwardly therefrom on opposed sides of the plate 11. The clamping members 40 and 41 are provided with over-sized bores 40' and 41', respectively, as shown in Figure 3, which are loosely penetrated by the shaft 26 so the members 40 and 41 may be swung outwardly relative to the web 19 of the rail 12 in removing the same from the rail as will be later described.

The lower portions of the clamping members 40 and 41 have flanges 42 and 43 secured, as by welding, to their inner sides. These flange portions 42 and 43 may be cast integrally with the clamping members 40 and 41, respectively, if so desired. The clamping members 40 and 41 extend downwardly to a point below the head portion 18 of the rail 12 and the flange portions 42 and 43 are adapted to fit under the head portion 18 of the rail 12 and serve to clamp the block to the rail.

The cam shaft 26 is further connected to the shaft 30 by means of arms 45 and 46 which extend in a substantially horizontal plane on opposed sides of the plate 11 and are fixedly secured at their right-hand ends in Figures 1 and 2 to said shaft 26 by welding or a pressed fit. The left-hand ends of the arms 45 and 46 are slidably penetrated by the shaft 30.

Now, in order to provide a means whereby the clamping members 40 and 41 may be placed in proper position against the rail 12, wedging members 50 and 51 are disposed on opposed sides of the plate 11. The wedging members 50 and 51 are substantially rectangular in shape and are loosely penetrated at their left-hand ends in Figures 1 and 2 by the shaft 30 so the wedging members 50 and 51 may freely pivot upon the shaft 30. The wedging members 50 and 51 normally extend horizontally to a point past the cam shaft 26 and past the right-hand ends of the rocker arms 27, 28, 45 and 46. The wedging members 50 and 51 are each provided with a notch 52, only one of which is shown in the member 50 in Figure 2. These notches 52 are of a size somewhat larger than the diameter of the cam shaft 26 and their surfaces nearest the shaft 30 are cut at an angle, as at 52'. The notches 52 thus provide another surface 49 which is beveled as at 49' so when the wedging members 50 and 51 are driven into place the notches 52 will fit over the cam shaft 26. The lower portions of the surfaces 52' of the wedging members 50 and 51 are beveled as at 53 and 54, respectively, as best seen in Figure 3. The beveled surfaces 49' and 53 and 54 are provided for easy insertion of the wedge members 50 and 51 between the members 45 and 40 and 46 and 41, respectively.

It is thus seen that when the block is to be placed on a rail the wedging members 50 and 51 will be in the raised dotted line position shown in Figure 2. The clamping means 40 and 41 are then moved adjacent the arms 45 and 46 so that when the block 10 is placed upon the rail 12, the

proximate edges of the flange portions 42 and 43 of the clamping members 40 and 41 will clear the remote vertical surfaces of the head 18 of the rail 12. The clamping members 40 and 41 are then moved inwardly to a point adjacent the rocker arms 27 and 28 so their flange portions 42 and 43 will bear against the medial portion 19 and the under side of the head portion 18 of the rail 12. The wedging members 50 and 51 are then driven between the clamping members 40 and 41 and the arms 45 and 46 to the solid line position shown in Figure 2 to thus tightly secure the clamping members 40 and 41 against the rail 12.

It should be further noted that the scotch block 10, as described, may be used on rails of different sizes by driving the wedging members 50 and 51 a greater or lesser distance between the clamping members 40 and 41 and the arms 45 and 46.

Suitable collars 55 and 56 fit around the shaft 30 and are welded thereto as at 57 and 58. These collars 55 and 56 are of a width substantially the same as the upper portions of the clamping members 40 and 41 and serve to hold the wedging members 50 and 51 in proper spaced relation to the plate 11.

It is thus seen that the cam shaft 26 and the shaft 30 are connected together by the rocker arms 27 and 28 closely adjacent the plate 11 and by the additional arms 45 and 46 spaced apart from the rocker arms 27 and 28 and that all of these arms 27, 28, 45 and 46 are fixedly secured to the cam shaft 26 at their right-hand ends in Figures 1 and 2 and are loosely or slidably penetrated by the shaft 30 at their left-hand ends. The shaft 30 is free for movement in the slot 16 and it is clear that upward movement of the shaft 30 will tend to move the arms 27, 28, 45 and 46 upwardly at their left-hand ends in Figures 1 and 2 and downward movement of the shaft 30 will move the arms 27, 28, 45 and 46 downwardly at their left-hand ends in Figure 2.

It should be noted that the slot 16 is arcuate but that the center point of its arc is not the same as the center of the cam wheel 25 but is somewhat to the left thereof in Figure 2.

Now, presuming the scotch block may not have been tightly secured to the rail 12, when the wheel 14 of a car strikes the face portion 13 of the plate 11, the plate 11 will tend to slide to the right in Figure 2, a slight distance, and this sliding movement will pull the portion 38 tightly against the base 20 of the rail 12 and will pull the shaft 30 towards the bottom of the arcuate slot 16. The downward pressure of the shaft 30 will urge the left-hand ends of the rocker arms 27 and 28 downwardly, and, due to the off center relation of the cam shaft 26 and the cam 25, the right-hand portions of the rocker arms 27 and 28 will move upwardly and to the left thus moving the cam 25 in a counterclockwise direction in Figure 2 and pulling the clamping members 40 and 41 upwardly against the lower surface of the head 18 of the rail 12 and to tighten the block securely against the top of the rail 12 to prevent further sliding movement of the scotch block 10.

It is thus seen that the block 10 may be placed on a rail and the wedging members 50 and 51 driven into position by a suitable mallet to urge the clamping members 40 and 41 against each side of the rail. The yoke member may be placed in position and the nuts 39 and 39' may be tightly secured to hold the block tightly against the rail. With the block thus secured, there will be very

little sliding movement of the block, but any sliding movement will tend to tighten the block against the rail rather than loosen it as has heretofore been the case.

It should be noted that the arcuate slot 16 extends upwardly and rearwardly so the yoke member 35 may be secured to the shaft 30 without removing the block 10 from the rail 12. This is accomplished by moving the shaft 30 upwardly in the slot 16 to a point above the ends of the arms 36 and 37 of the yoke 35 and then the shaft 30 is moved downwardly so the members 36 and 37 will enter the bores 31 and 32 in the shaft 30 after which the nuts 39 and 39' may be driven home on the threaded portions of the members 36 and 37.

The length of the slot 16 in the plate 11 and its curvature relative to the cam 25 provide for ease in mounting the scotch block 10 on the upper surface of the rail 12 and also for ease in removing the scotch block 10 from the rail 12.

In removing the scotch block 10 from the rail 12, the nuts 39 and 39' are removed from the upper ends of the threaded arms 36 and 37 of the yoke 35 and then the shaft 30 is moved upwardly along the slot 16 and, in so doing, the cam 25 is partially rotated in a clockwise direction in Figures 2 and 4. This partial rotation of the cam wheel 25 will move the shaft 26 downwardly, which will, in turn, move the flanges 42 and 43 of the clamping members 40 and 41 downwardly out of engagement with the lower surfaces of the head 18 of the rail 12 and to where the members 40 and 41 may be moved outwardly, it being understood that the members 50 and 51 must be moved to the dotted line position shown in Figure 2 prior to the members 40 and 41 being moved outwardly. Since the head 18 of some rails is larger than others, the oversize bores 40' and 41' in the members 40 and 41 permit the members 40 and 41 to be swung outwardly so as to clear remote surfaces of the head 18 of rail 12. The members 40 and 41 may then be swung about the shaft 26, their flanges 42 and 43 moving past the remote surfaces of the head 18 of the rail 12 and then the scotch block 10 may be lifted off of the rail 12.

Now, when mounting the scotch block 10 on the rail 12, it is merely necessary to position the clamping members 40 and 41 with their flanges above the shaft 26 and then the shaft 30 is positioned at the highest point in the notch 16 after which the clamping members 40 and 41 are swung downwardly and then moved inwardly to the position shown in Figure 3. The shaft 30 is then moved downwardly as the threaded arms 36 and 37 are inserted therein in the manner heretofore described, to thus clampingly secure the scotch block 10 to the upper surface of the rail 12.

Referring now to Figures 6, 7 and 8, a modified form of the invention may be observed wherein a modified form of yoke member is used, the particular object of this modification being to provide a block which can be tightly secured to the top of the rail without the necessity of having an anchoring member disposed underneath the rail. With the exception of the yoke member the parts are like those shown in Figures 1 to 5 inclusive, and like reference characters will be used for those parts.

The shaft 30 is also the same in both forms of the invention and is mounted in the plate 11 in a like manner. Penetrating the bores 31 and 32, in opposed ends of the shaft 30 are bolts 61 and 62, respectively, which are threaded at their

upper ends for reception of the nuts 39 and 39'. The lower portion of the bolts 61 and 62 penetrate opposed ends of a horizontally disposed plate member 63 which extends beneath the plate 11. In this modified form of the invention the plate 11 has a notch 65 cut therein at its base portion which is loosely penetrated by the plate member 63. The plate member 63 is preferably of a thickness the same as, or slightly greater than, the depth of the notch 65 so that when the scotch block 10 is in position on the rail 12, the lower surface of the plate 63 will always be in engagement with the top surface of the head 18 of the rail 12 as at 66. It should be noted that the notch 65 is somewhat wider than the width of the plate 63 so the plate 63 may have a limited amount of sliding movement in the notch 65 (Figure 8).

Now, when the scotch block 10 is placed on the rail 12 in the manner heretofore described, and the wedging members 50 and 51 have been driven home to secure the flanges 42 and 43 of the clamping members 40 and 41 against the rail 12, the nuts 39 and 39' are driven tightly against the shaft 30 to urge the shaft 30 toward the bottom of the slot 16 and to thus urge the rocker arms 27 and 28 downwardly at their left-hand ends in Figure 6 and upwardly at their right-hand ends. This will cause the cam wheel 25 to move in a counterclockwise direction to urge the flanges 42 and 43 of the clamping members 40 and 41 tightly against the lower surface of the head 18 of the rail 12 to prevent sliding movement of the scotch block 10 on the rail 12.

In this modification the nuts 39 and 39' should always be tightly secured against the rod 36. However, in the event these nuts 39 and 39' should become loosened, or may not have been tightened sufficiently, the plate 63 will be in frictional engagement with the rail 12 and upon impact of a car wheel 14, the plate 11 will slide slightly relative to the plate 63 against the rail and will cause the shaft 30 to move downwardly toward the lower portion of the slot 16 thus pulling the flanges 42 and 43 of the clamping members 40 and 41 into tighter engagement with the lower surface of the head 18 of the rail 12 in the manner heretofore described.

In the drawings and specification there has been set forth a preferred embodiment of the invention, and although specific terms are employed, they are used in a generic and descriptive sense only, and not for purposes of limitation, the scope of the invention being defined in the claims.

We claim:

1. In a wheel stop of the type adapted to be mounted upon a rail having a head flange and to slide a small amount thereon upon car wheel impact, bracket means slidably mounted in one portion of said stop and extending therebeneath in frictional contact with said rail, a cam rotatably mounted in another portion of said stop and spaced from said bracket means, depending clamping means associated with said cam and supported thereby for clampingly engaging said rail, rocker arms connecting said bracket and said cam, whereby impact of a car wheel against said stop will move said bracket to actuate said cam through said arms thereby causing movement of said clamping means against said rail.

2. A scotch block of the type adapted to be mounted on a rail and being engageable by a car wheel for stopping movement of the same comprising a vertically disposed plate member having

an arcuate slot in the front portion thereof and having a circular bore in the rear portion thereof, the radius point of the arcuate slot being disposed below the center point of the circular bore, said plate having a curved surface at one edge conforming substantially to the curvature of a car wheel adapted to be engaged thereby, a cam oscillatably mounted in the circular bore, a cam shaft fixedly mounted in the cam in off center relation thereto remote from the arcuate slot, a transverse shaft loosely penetrating said arcuate slot, arms connecting the transverse shaft with the cam, at least one depending member oscillatably mounted on the cam shaft, said rail having a head portion integral therewith, means on the depending member adapted to engage the lower surface of the head portion, and means on the plate for moving the transverse shaft downwardly toward the rail upon car wheel impact, whereby the movement of said transverse shaft downwardly will transmit partial rotation to the cam to cause the cam shaft to be moved upwardly or about the axis of the cam to thereby tighten the flange portion of the depending member against the lower surface of the head portion of the rail.

3. A scotch block adapted to be mounted upon a rail comprising a vertically disposed plate having a concave surface at its edge for engagement by a car wheel, a transverse shaft loosely penetrating the front portion of said vertically disposed plate and having up and down movement in said plate, a cam rotatably mounted in the rear portion of said plate in spaced relation to said transverse shaft, an eccentrically positioned cam shaft penetrating said cam, said cam shaft being positioned rearwardly of the axis of the cam relative to the concave surface of the plate, arms connecting said transverse shaft with said cam shaft, depending members oscillatably connected to the cam shaft adjacent opposed sides of said vertically disposed plate, flanges on the proximate lower surfaces of the depending members and adjustable means secured to the transverse shaft and in frictional contact with the rail, said projections on the depending members being disposed a substantial distance below the lower surface of the vertically disposed plate, whereby impact of a car wheel against the curved surface of the vertically disposed plate will move said plate a small amount along the rail causing the adjustable means contacting said rail to be biased to pull the transverse shaft downwardly to transmit partial rotation to the cam wheel through the connection arms, thus causing the cam shaft to move upwardly to tighten the projections on the depending members against the lower surfaces of the head portion of the rail.

4. A wheel stop of the type adapted to be mounted upon a rail and to slide a small amount thereon under car wheel impact comprising a plate upstanding in the vertical plane of the rail, said plate having an arcuate slot in the front portion thereof, a horizontal shaft slidably disposed in said slot, a yoke member secured to the shaft and extending beneath the rail for securing the stop to the rail, a cam mounted in the rear portion of said stop, depending clamping members associated with said cam, rocker arms connecting the shaft with the cam, whereby upon car wheel impact the yoke member will urge the shaft downwardly in the arcuate slot and away from the center of the cam to cause the rocker arms to partially rotate the cam thereby urging the clamping members associated therewith into

tight engagement with the rail to prevent movement of the stop on the rail.

5. A wheel stop of the type adapted to be mounted upon a rail and to slide a short distance thereon under car wheel impact comprising a plate upstanding in the plane of the rail and having its forward end of concave formation to form an abutment for the car wheel, said plate having an arcuate slot in the front portion thereof, a horizontal shaft slidably disposed in said slot, bracket means secured to the shaft and extending beneath the rail for securing the stop to the rail, cam means rotatably mounted in the plate, a cam shaft penetrating said cam means, rail clamping means associated with said cam shaft, rocker arms connecting the horizontal shaft with the cam shaft, wedging means pivotally mounted at one end on said horizontal shaft and having notches in their other ends for engaging the cam shaft adjacent the clamping means to thus urge the clamping means against the rail, whereby upon car wheel impact the bracket will urge the horizontal shaft downwardly in the arcuate slot to cause the rocker arms to partially rotate the cam means elevating said cam shaft to urge the clamping means associated therewith into tighter engagement with the rail to prevent movement of the stop on the rail.

6. A scotch block of the type adapted to be mounted on a rail and to slide thereon slightly under car impact comprising a plate upstanding in the plane of the rail and having its forward end of concave formation to form an abutment for the car wheel, said plate having an arcuate slot in the front portion thereof, a horizontal shaft slidably disposed in said slot, bracket means removably secured to the shaft and extending beneath the rail for securing the block to the rail, said shaft being movable vertically in the arcuate slot so the bracket may be removed from said shaft without removing the block from the rail, a cam shaft having a cam thereon rotatably mounted in the rear portion of the plate, clamping members depending from said cam shaft and having means thereon for engaging said rail, rocker arms connecting the first-named shaft with the cam shaft and cam thereon additional rocker arms spaced apart from the first-named arms and connecting the first-named shaft with the cam shaft, wedging means pivotally mounted at one end thereof on the first-named shaft and having notches in their other ends for engaging the cam shaft to thus urge the clamping means against the rail, whereby movement of the plate, upon car wheel impact, will move the bracket means to urge the first-named shaft downwardly in the arcuate slot toward the rail causing the rocker arms to partially rotate the cam shaft to urge the clamping means into tighter engagement with the rail to prevent further movement of the block on the rail.

7. A scotch block of the type adapted to be mounted on a rail and to slide slightly thereon under car impact comprising a plate upstanding in the plane of the rail and having its forward end of concave formation to form an abutment for the car wheel, said plate having a slot in the front portion thereof, a transverse shaft slidably mounted in said slot, a yoke removably secured to the shaft and extending beneath the rail for securing the block to the rail, a cam shaft having a cam thereon rotatably mounted in the rear portion of the plate, clamping members depending from said cam shaft and having means thereon

for engaging said rail, two spaced rocker arms on each side of the vertical plate secured at one of their ends to the first-named shaft and secured at the other of their ends to the cam shaft and the cam means, said clamping means being disposed between said rocker arms, wedging means pivotally mounted at one end thereof on said first-named shaft and having notches in their other ends for engaging the cam shaft to thus urge the clamping means associated therewith against the rail, said wedging members being beveled at their lower ends to tightly secure the clamping means on rails of different width, whereby upon car wheel impact, the yoke will urge the first-named shaft downwardly in the slot towards the rail to move the rocker arms to cause the cam to partially rotate and urge the clamping means into tighter engagement with the rail to prevent further movement of the block on the rail.

8. A scotch block having a car wheel abutment structure vertically disposed in the plane of a rail having a head thereon and said scotch block being adapted to slide slightly along the rail under impact of a car wheel comprising a vertical plate having an arcuate slot in the front portion thereof, a horizontally disposed shaft loosely penetrating the arcuate slot, the shaft having bores therein at its opposed ends, a U-shaped member adapted to have its lower portion disposed underneath the rail and adjacent the base thereof and vertically extending portions adapted to penetrate the bores in each end of the shaft, the upper portion of the vertically extending portions being threaded, nuts adapted to be secured to the upwardly extending portions for securing the same to the shaft, the vertical plate also having a bore in the rear portion thereof spaced from the arcuate slot, a cam rotatably mounted in said bore, a cam shaft penetrating said cam and fixedly secured thereto, rocker arms disposed on opposed sides of the vertical plate and fixedly secured to the cam and the cam shaft at one of their ends and slidably penetrated by the first-named shaft at their other ends, a second pair of rocker arms disposed on opposed sides of the vertical plate and secured at one of their ends to the cam shaft in spaced relation to the first-named rocker arms and slidably penetrated at their other ends by the first-named shaft, depending clamping members oscillatably connected to the cam shaft on opposed sides of the vertical plate between the first-named and second-named rocker arms, flange portions on the lower proximate surfaces of the depending clamping members for engaging the rail, wedging members oscillatably mounted at one end thereof adjacent opposed sides of the vertical plate on the first-named shaft and having a notch in their other ends adapted to be fitted over the cam shaft, said wedging members being beveled on their lower surfaces, collar members on the first-named shaft adapted to hold the wedging members in spaced relation to the first-named rocker arms and adjacent the second rocker arms, whereby, upon the wedging members being driven home between the second rocker arms and the depending clamping members, the depending clamping members will be urged into tight engagement with the rail, and upon impact of a car wheel the vertical plate will move slightly pulling the first-named shaft downwardly in the arcuate slot, and to cause the rocker arms to partially rotate said cam to urge the depending clamping members upwardly into a tight clamping position against the lower surface of the head of the rail thus

11

preventing movement of the scotch block upon the rail.

9. A scotch block of the type adapted to be mounted on a rail to prevent movement of a car wheel thereon comprising a plate upstanding in the plane of the rail and having its forward end of concave formation to form an abutment for the car wheel, said plate having a slot in the front portion thereof, a shaft slidably disposed in said slot, a yoke removably secured to the shaft and having a lower portion extending beneath the plate in contact with the upper surface of the rail, said plate having a notch in its lower surface for the reception of the lower portion of the yoke, said notch being of the same depth as the thickness of the lower portion of the yoke but being slightly longer than the width of the lower portion of the yoke so the lower portion of the yoke will engage the upper surface of the rail and will have limited sliding movement in the notch, a cam shaft having a cam thereon rotatably mounted in the rear portion of the vertical plate, two spaced rocker arms positioned on each side of the vertical plate and secured at one of their ends to the first-named shaft and at their other ends to the cam shaft and cam means, rail clamping members depending from said cam shaft between said rocker arms, wedging means pivotally mounted at one end thereof on said first-named shaft and having notches in their other ends for engaging the cam shaft to thus urge the clamping means associated therewith against the rail, whereby upon wheel impact frictional contact of yoke against the rail will urge the shaft downwardly in the slot to cause the rocker arms to partially rotate the cam shaft to urge the clamping means associated therewith into tighter engagement with the rail to further tighten the block against the rail.

10. A scotch block adapted to be mounted on a railroad rail provided with upper and lower flanges comprising a transverse member adapted to rest on the upper surface of the upper flange of the rail and having threaded bolts slidably penetrating the same and extending upwardly therefrom, a transversely disposed shaft loosely penetrated by said bolts, said bolts having nuts on the upper ends thereof, a vertically disposed plate resting on the upper flange of the rail and having a notch in its lower surface fitting over the transverse member, said vertically disposed plate having an arcuate slot in the front portion thereof penetrated by said transversely disposed shaft, rocker arms disposed one on each side of

12

the vertically disposed plate and having one of their ends oscillatably mounted on the transversely disposed shaft, said vertically disposed plate having a circular cavity in the rear portion thereof, a second transversely disposed shaft penetrating said circular cavity and having a circular cam eccentrically secured thereon, said circular cam loosely fitting in said circular cavity in the vertically disposed plate, the other ends of said rocker arms being fixedly secured to said second transversely disposed shaft, a downwardly depending member loosely mounted on said second transversely disposed shaft on opposed sides of the vertically disposed plate, said downwardly depending members each being provided with an inwardly disposed flange adapted to fit beneath the top flange of the rail, a second rocker arm disposed on each side of the vertically disposed plate and in spaced relation to the first rocker arms, and having one of their ends oscillatably secured to the first transversely disposed shaft and having their other ends fixedly secured to the second transversely disposed shaft, wedging members disposed between each of the outermost rocker arms and the depending members, said wedging members being oscillatably mounted on the first transversely disposed shaft, said wedging members each having a notch in its lower surface adapted to fit over the second transversely disposed shaft and each of the wedging members having beveled lower portions adjacent the notches to provide an entering surface between the outermost rocker arms and the adjacent depending members so that when the wedging members are driven between the rocker arms and the downwardly depending members, the downwardly depending members will have their free ends moved inwardly forcing the inturned flanges on the downwardly depending members against the sides of the rail, whereby upon car wheel impact said transverse member will actuate said cam through said rocker arms to urge said downwardly depending members into tighter engagement with said rail.
